UNITED STATES PATENT OFFICE.

ALFRED BRADY, OF NEW YORK, N. Y.

IMPROVEMENT IN BATHING-TUBS.

Specification forming part of Letters Patent No. 43,002, dated June 7, 1864.

To all whom it may concern:

Be it known that I, ALFRED BRADY, of the city, county, and State of New York, have invented an Improvement in Bathing-Tubs; and I do hereby declare that the following is a full and exact description thereof, reference being had to the accompanying drawings, and to the letters of reference marked thereon, making part of this specification.

A is the tub with the waste-hole b placed near the side or end of the tub, and connecting with the waste-pipe e under the tub. c is the overflow-hole. d is the overflow-channel, placed on the inner side of the tub, and cast as a part of its side or end, and directly over part of the waste-hole b. f is a hole at the top of the overflow-channel, sufficiently large for the inserting a rod, wire, or other substance to remove any obstruction in the overflow-channel or waste-pipe.

To enable those skilled in the business of making sinks or basins to make them with my invention and improvement, I proceed to describe its construction and operation. I cast the tub or basin A in any of the known forms, except that I have the side where the overflow-channel d is placed straight. I cast the overflow-channel d on the inside of the tub and forming part of its side or end. I have the waste-hole b placed close up to the side or end of the tub and extending partly under the end of the overflow-channel. I have a sieve or plate, G, with holes in it, to place over the waste-hole to allow the water and small particles to pass through, but to prevent large pieces of dirt or other matter from passing into the waste-pipe. This plate or sieve G, I fasten over the waste hole, with screws, which, at the same time, pass through and fasten the flange that holds the waste-pipe e to the bottom of the tub and to the waste-hole. The sieve or plate G fits

tight around the outside of the overflow-channel, and also to the bottom of the tub over the waste-hole. Thus the overflow-channel, part of the waste-hole, and the waste-pipe form one straight, continuous channel from near the top of the tub A to any required distance into the waste-pipe, and at the same time leaving the waste-hole sufficiently large into the tub to drain the tub, thereby diminishing the liability of either the overflow-channel or waste-pipe becoming obstructed. I have an opening in the top of the overflow-channel sufficiently large for a rod or other substance to be put in to clear out the channel or waste-pipe, in case either should become obstructed. It will be perceived that this arrangement is equally well adapted to basins, siuks, and water-closets.

What I claim as my invention and improvement, and desire to secure by Letters Patent, is—

The construction, combination, and arrangement of the overflow-channel, the waste-hole, and waste-pipe, as described in the above specification, the overflow-channel being placed on the inside of the tub, so as to bring the overflow-channel over part of the waste-hole and waste-pipe, thereby forming one straight and continuous channel from the top of the overflow-channel into the waste-pipe, the opening in the top of the overflow-channel being sufficiently large for removing obstructions in the overflow-channel or waste-pipe, all as shown and described.

Dated New York, February 22, 1864.

ALFRED BRADY.
